FIG. 2

FIG. 1

FIG. 3

FIG. 4

FIG. 6

FIG. 5

FIG. 7

FIG. 1 is a side elevational view of the movable sprayer showing my new design;

FIG. 2 is a top plan view thereof on an enlarged scale;

FIG. 3 is a side elevational view taken from the left hand side of FIG. 2;

FIG. 4 is a bottom plan view of the sprayer of FIG. 2;

FIG. 5 is a side elevational view taken from the right hand side of FIG. 2; and

FIGS. 6 and 7 are cross sectional views, on a further enlarged scale, taken along the lines 6—6 and 7—7 respectively of FIG. 2.

The coupling and fragmentary section of hosing are shown in broken lines for illustrative purposes only. The handle is broken away in FIGS. 2 through 5 for convenience of illustration.

The dominant features of my design reside in those features shown in full lines.

I claim:

The ornamental design for a movable sprayer, as shown and described.
